UNITED STATES PATENT OFFICE.

RICHARD KELLENDORFER, OF MUNICH, GERMANY, ASSIGNOR TO BAYERISCHE ELEKTRIZITÄTS-INDUSTRIE ROTT & CO., OF MUNICH, GERMANY, AND AART PIETER VISSER, OF ROTTERDAM, NETHERLANDS.

ELECTRIC STARTING APPARATUS.

Application filed September 15, 1924, Serial No. 737,939, and in Germany May 5, 1923.

This invention relates to a tilting switch intended to be used as an electric starter and it consists in this that a solid tilting resistance is inserted in the circuit of the apparatus or machine to be started and that said resistance is gradually short-circuited during the tilting by an electrically conductive liquid.

The electrically conductive liquid may 10 consist of mercury.

The tilting switch constructed according to the invention may be connected to the apparatus or machine in different ways according to the particular application.

15 When the switch is used for starting a continuous current motor it is preferably inserted in the armature circuit. When it is used for the starting of a three-phase motor with short-circuit armature it is preferably

20 inserted in the circuit of the rotor and after the tilting, and when in its end position, it inserts the short-circuit connections between the rotor windings. When it is used for the

25 starting of any other three-phase motor it is inserted in the stator leads thereby connecting the stator winding directly onto the supply circuit or to the feeding transformer at the end of its tilting movement. It is however to be understood that the starter 30 according to the present invention may be connected in any other way.

The great advantage of the apparatus according to the present invention consists in this that the disconnection of the starting resistances is effected gradually without any 35 sparking being produced. Moreover by suitably choosing the form of the resistance that is gradually short-circuited by the electrically conductive liquid, any desired starting

40 characteristic may be obtained. Thus use may be made of a resistance, the cross section of which is uniform or varies according to a definite law; similarly the channels through which the liquid flows and in

45 which it rises during the tilting may be made of any desired form thereby causing that during a uniform tilting movement, the disconnection of the resistances is effected in equal steps which are exceedingly small,

50 or that during the disconnection the inserted resistance decreases uniformly or more quickly or more slowly according to the general requirements that have to be fulfilled

with respect to the apparatus or machine that is to be connected up.

55 Instead of adapting the starter according to the invention to the electric requirement of the starting operation, the mechanical tilting movement may be effected according to a predetermined law, for instance in such a manner that the controlling lever, in spite of its uniform controlling movement, effects a different tilting movement of the starter such as by using a cam or other suitable transmission mechanism interposed between 60 the lever and the starter. In this way, if the controlling lever is operated at a uniform speed, during the starting operation the electrical part of the starter will, in spite of this, follow a different law when 65 moving from its disconnected into its short-circuiting position. Link mechanisms, cam discs and other mechanical arrangements may be used for transmitting the motion required in these cases.

70 Instead of, or in addition to, the mechanical transmission means just referred to, use may be made of braking devices either acting upon the controlling lever or, in the case when there is an elastic connection between 75 the electrical part and the controlling member for instance a spring, on one of these transmission means or on a stopping device or the like, in order to cause the starting to follow a definite law or in order to ensure a 80 definite speed of starting.

85 The starter according to the invention may also be used for disconnecting the controlled apparatus or machine. Generally the law that the starting operation has to follow 90 is followed in the opposite direction when the apparatus or machine is disconnected. In that case the switch can be used for controlling the two operations. When this is not the case the movement to be performed 95 during the disconnecting operation has to follow the law that is required for that purpose. As the electric components as such cannot be altered, the mechanical driving or stopping device used for the disconnection 100 must be different from that used for the starting. This switching-over may for instance be effected by causing the fixing means to follow in a known manner two different paths during the starting and its disconnecting operation respectively. For this 105

purpose the said fixing means is preferably guided in two slits one of which is provided for the starting operation and the other one for the disconnecting operation, and the controlling member when reaching its end positions, is shifted over by a transverse movement from the one slit into the other as is well known in the art.

The invention also consists in two forms of construction of a tilting switch as above referred to. The resistances which are to be short-circuited by the electrically conductive liquid are mounted in a conducting casing, being connected at one end to the latter and provided at the other end with electric terminals outside the casing and insulated therefrom. The starter is inserted into the circuit to be controlled, being connected thereto through the conducting casing and through the said terminals. The conducting casing is also provided with a chamber for the reception of the short circuiting liquid and passages in the proximity of the resistances and also with inlet and outlet openings or conduits for the short-circuiting liquid which are provided in such a manner that when the apparatus is tilted for starting purposes the liquid flows from the said chamber into the passages in the proximity of the resistances and can rise along the latter in direct contact therewith until the resistances are short-circuited, whilst during the tilting for disconnecting the apparatus or machine the same or other openings or passages are used through which the short-circuiting liquid returns from the short-circuiting passages into the chamber above referred to.

Various forms of construction for carrying the invention into effect are illustrated by way of example in the accompanying drawings.

Figure 1 is a sectional elevation of a starter intended for use in connection with three-phase current.

Figure 1^a is a sectional plan view along the line I—I of Figure 1.

Figure 2 is a sectional elevation of another form of construction.

Figure 2^a is a transverse section along the line II—II in Figure 2.

Figure 3 is an elevation of another form of construction.

Figure 4 is a sectional elevation of another form of construction intended for use in connection with three-phase current, Figure 4^a being a section along the line IV—IV in Figure 4.

Figures 5, 6 and 7 show various diagrams of connection to be used with the improved starter.

Figure 8 is a sectional elevation through a starter according to the invention for three-phase current, Figure 9 being a sectional plan view of the same form of con-

struction and Figure 10 a sectional end elevation thereof.

Referring to Figures 1 and 1^a, 1 is a casing of conducting material which is made slightly conical and contains three resistances 2, 3 and 4, a space 12 being left free between them and the casing; each of these resistances is a portion of a cone, its lower end either being in direct contact with the casing 1 or being separated therefrom, the upper ends of the resistance being provided with terminals 5, 6 and 15 which pass outside the casing through the upper cover thereof, being insulated therefrom. The casing 1 is also provided with a chamber 7 for the reception of the liquid the wall 9 of this chamber being preferably made of the same material as the casing 1 and in one piece therewith. A passage 22 leads from the chamber 7 to the opening 23 leading to the intermediate space 12. The latter communicates with the space 17 from which the liquid passes through an opening 21 into an overflow pipe 8 which communicates by openings shown at the lefthand end thereof with the chamber 7. For manufacturing reasons the passage 22 is carried as far as the end of the casing 1 and is then sealed up by means of a stopper 24 which may for instance be screwed on. The whole of the device is mounted on the rotary axle 11.

The resistances 2, 3 and 4 are separated from one another by walls 14 of insulating material so that the resistances are positively insulated from one another at their upper ends as is also the case with the terminals 5, 6 and 15.

In the case of a short-circuit induction motor the device hereinbefore described is applied as follows: The three ends of the three-phase rotor winding are connected to the terminals 5, 6 and 15 through the slip rings. If the resistances 2, 3 and 4 are conductively connected with the casing 1, a small magnetizing current limited by these resistances can be induced in and flow through the armature immediately upon the stator being inserted into the circuit. However if the resistances are insulated from the casing 1 no current will as yet flow through the rotor. This first position is attained when the device illustrated in Figure 1 is tilted through about 90° in an anti-clockwise direction in which case the conductive liquid lies entirely in the chamber 7.

Now, if the device is tilted in a clockwise direction the liquid flows through the passage 22 and opening 23 into the intermediate space 12 whereby a conductive connection is effected between the three resistances, corresponding parts of the resistances being gradually disconnected. When the device reaches the position illustrated in Figure 1, the liquid has completely left the chamber 7 and has passed over into the in-

termediate space 12, standing therein and also in the passage 2—which does not come into question as regards the starting—at such a height that it completely covers the 5 outer surface of the resistances 2, 3 and 4, covering also the connecting sleeves 80, as is indicated by the level 81. When the device is in this position the starting has already been effected, the resistances 2, 3 and 4 being 10 completely disconnected and the rotor being short-circuited.

When the device is tilted back in an anti-clockwise direction the liquid flows back into the chamber 7 partly through the passage 22 and partly through the passage 17, 15 opening 21 and overflow pipe 8.

The casing and the resistance have purposely been made of conical shape in order to ensure a complete return of the liquid and 20 the overflow pipe 8 has been provided in order to prevent an unintentional return of the liquid for instance through the opening 22 during the starting operation. It is however to be understood that the casing and 25 the resistances may be made of any other shape. For instance they may be made of asymmetrical shape with the object of ensuring a uniform disconnection of the resistances 2, 3 and 4, it being clear that during 30 the starting operation the resistance 2 and partly the resistance 4 will in the first instance be covered by the liquid to a larger extent than the resistance 3, the three resistances being equally covered after the final 35 short-circuiting passage has been attained. However the latter conditions can be effected by suitably shaping the resistances and the passages.

A form of construction in which this 40 asymmetry of the starting and disconnecting operation which is sometimes disturbing in practice is absent, is illustrated in Figures 2 and 2^a. The parts corresponding to those hereinbefore described with reference 45 to Figures 1 and 1^a have been indicated by the same reference letters. The resistances 2, 3 and 4 have again been shown therein as being of tapered shape for the reasons hereinbefore given. The overflow pipe has 50 not been shown, for the sake of simplicity, seeing more especially that it is not always required. The arrangement differs from that hereinbefore described in this, that the resistances 2, 3 and 4 are arranged one after 55 the other, so that when the device is tilted into the position shown on the drawing, which is the starting position, all the resistances are uniformly and gradually short-circuited according to the same law.

60 In this form of construction the resistances 2, 3 and 4 are insulated from the conducting casing and from one another by means of an insulating material 16, 18, a suitable insulator 82, 20 being provided at the upper part of the device, and a passage

17 leading to a return opening 21 provided in the latter insulator for each individual resistance. The terminals 5, 6 and 15 pass through the lid 19 of the device, being suitably insulated therefrom. 70

Assuming it is desired to connect the device to the three phases of the rotor of a short-circuit motor through the three terminals 5, 6 and 15, as in the case of the arrangement illustrated in Figures 1 and 1^a, 75 the operation is as follows:

When the device is in its disconnected position (not shown on the drawing) the liquid is exclusively contained in the chamber 7. By tilting the device in clockwise 80 direction the liquid flows through the passages 22 and openings 23 first of all in the space 12 shown on the lefthand side of Figure 2^a and whence through passages 83 provided in the insulating casing 18 into the 85 passage 12 shown on the righthand side of Figure 2^a, the liquid rising therein as the tilting continues, until it touches the sleeves 80 whereby the resistances 2, 3 and 4 are 90 short-circuited and entirely disconnected.

In this arrangement the resistances 2, 3 and 4 as well as the passages 12 and 22 are assumed to be of rectangular cross section. As will be seen from Figure 2^a, the walls 16 do not touch the passages 12, so that the 95 liquid in these passages covers in a continuous manner all the three resistances simultaneously. However, it is not absolutely necessary that the walls 16 should terminate in the manner described as they may extend 100 in the manner described as they may extend until they reach the inner surface of the casing 1, since the casing 1 is of conducting material and the current flows for instance from the sleeves 80 through the liquid to the 105 casing and is short-circuited by the same. This is also one of the reasons why the casing 1 has to be made of conducting material. Another ground therefor is that it is easy 110 to manufacture it of metal. It is however to be understood that in this form of construction as well as in any of the other forms herein described for carrying the invention into effect, the casing may be made of non-conducting material, the current being conducted and short-circuited solely through 115 the liquid.

If the device is tilted from the position shown in Figure 2^a in an anti-clockwise direction in order to effect the disconnection, the liquid will flow partly through the passage 22 and partly through the passage 17 and the opening 21 completely back into the chamber 7. 120

It will be clearly seen that a complete interruption of the current will take place 125 only when the various resistances are insulated from the conducting casing 1 or when the casing 1 is not made of conducting material. It is possible to interrupt the current outside the starter and it is often desir- 130

able and sometimes stipulated that the circuit should be completely interrupted at least from the one pole of the machine or apparatus.

3 A simple form of construction intended for this purpose is diagrammatically illustrated in Figure 3 in connection with the device for instance as illustrated in Figure 2. It is assumed that the device is not used 10 for starting a motor armature but for starting the stator winding or another apparatus. The supply circuit is connected onto the terminal 27 (Figure 3) which is connected with a fixed contact 26. The casing 1 is 15 electrically connected with a knife contact 25 which is pivoted at 11. In the disconnected position (not shown on the drawing) the knife contact 25 is not in contact with the fixed contact 26. At the beginning of 20 the movement for effecting the connection the knife contact 25 is moved into the contact 26 being in advance of the tilting movement of the starter, the supply circuit being thus connected up. As the tilting continues, 25 the resistances are short-circuited and the apparatus finally receives the full voltage of the supply circuit. The apparatus is connected thereto with the terminal 5 which is connected to the resistances in the manner 30 shown in Figure 2.

The apparatus hereinbefore described may be used alone or in combination with several similar apparatus, in connection with continuous alternating current or three-phase 35 current.

In the various forms of construction hereinbefore described the resistances 2, 3 and 4 have been assumed to be insulated from one another in order to be able to control the 40 individual phases separately. This however, is not absolutely necessary. Moreover the apparatus according to the invention may also be used for other purposes. Another form of construction showing the application 45 of the invention to another apparatus is illustrated in Figures 4 and 4^a.

Referring to Figures 4 and 4^a let us first of all assume that it is desired uniformly 50 to start three different apparatus which are connected together in parallel. Moreover the construction is such that the non-uniform starting of the different phases in the case of an induction motor by means of an apparatus as illustrated in Figure 1, is prevented.

In this case the resistances 2, 3 and 4 are made of cylindrical form. The terminals 5, 6 and 15 are extended into sleeves 28, 29 and 30 or are connected therewith, these 60 sleeves being completely inserted in the resistances. An immediate short-circuit between these sleeves for instance through the conducting casing 1 or by the first admission of the liquid, is prevented by the insulating insertions 84 which are provided all

round and subdivide the passage 12. The sleeves lie directly next to the passage 12 only at the upper edge as is illustrated in Figure 4^a.

When used as a starter for an induction 70 motor the form of construction just referred to operates as follows: The starter is tilted through an angle of approximately 90° from the position indicated in Figure 4 in counter-clockwise direction so that the liquid lies 75 in the chamber 7 and in a portion of the passage 22. During the tilting the liquid flows into the passage 22 and finally rises through the opening 23 in the three passages 12 between the insulating insertions 84 until 80 it reaches the level 81 indicated in Figure 4^a, and short-circuits the three sleeves 28, 29, 30. When the apparatus has returned into its original position the liquid flows back along the same path from the passage 85 12 and more particularly through the opening 21 along the partition wall 33. It is advisable to tilt the starter back into the position illustrated in Figure 4^a through an angle of more than 90°. The motor winding 90 is connected to the terminals 5, 6 and 15 and in any case a minimum current will flow through the armature when the stator is connected up, which minimum current is determined by the resistances 2, 3. The apparatus 95 operates in a similar manner when the supply circuit is connected to the sleeve 31 whilst one pole of the consuming apparatus is connected to the terminal 5, 6, 15. In the original position the current will flow 100 from the terminal 32 through the resistances 4, 3 and 2 to the terminals 15, 5, 6, the resistances being gradually disconnected during the tilting and being gradually inserted during the return tilting movement.

The arrangement just described also shows how an induction motor can be started with only two resistances 2 and 3 since the resistance 4 and the terminal 32 may be dispensed with.

It is also to be pointed out that the passage 12 shown on the righthand side in Figure 4 is filled up with liquid only when the same has risen to such a height that it passes the upper recess of the insertion 84 and enters 110 into this passage 12.

In the forms of construction hereinbefore described the starting resistances are arranged in one single casing and the short-circuit takes place through the contact liquid 120 itself. However the same result may be obtained by providing separate devices each of which embodies one single resistance. In that case a single apparatus may be inserted in each conductor when the invention is applied to a multi-phase arrangement of alternating current or to a double pole connection of continuous current which apparatus 125 comprises a solid resistance capable of being tilted and short-circuited or inserted into 130

the circuit by a conducting liquid during the tilting.

Various diagrams of connections with such separate apparatus will now be described, separate switches being used in this case in order to effect a complete disconnection of the starter from the circuit to be controlled.

Referring to Figure 5, 34 is the stator of an induction motor which is connected through the main switch 35 to the supply circuit the rotor being connected through the slip rings with the separate and insulated casings 1 of a starter according to the present invention. The resistances 2, 3, 4 have to be short-circuited together as indicated at 38. 50 are the insulating terminals of the casings 1 which terminals are insulated from one another. 36 are the terminals by which the stators are connected to the switch 35 and 37 are the terminals by which this switch is connected to the supply circuit.

All the three starting resistances are secured to a common tilting axle 11 (indicated in dotted line) which also moves the knife contacts 35 in such a manner that the said knife contacts 35 effect the contact immediately at the commencement of the starting operation and remain in the contact position until the tilting apparatus reaches its initial position during the disconnecting operation.

Figure 7 illustrates a diagram of connections intended for a continuous current or alternating current shunt machine. The connections will be readily understood. The field winding 39 is first inserted into the circuit by the switch 35 and thereupon the armature 40 is gradually inserted into the circuit through the intermediary of the tilting apparatus 1, 2 according to the invention.

All the required movements for the operation of the tilting apparatus and of the main switch are derived in a positive mechanical way from the movement of the controlling lever for instance by means of stops, cams, etc.

Figures 8, 9 and 10 illustrate, by way of example, arrangements which may be used with the diagram of connections illustrated in Figure 5.

Each of the three casings 1 together with its axle 11, is pivotally mounted on a conducting supporting arm 51 connected to the terminal 50. These are the terminals to which the stator, illustrated in Figure 5, is connected.

The resistances 2, (see Fig. 10) are connected to the terminals 5, 6 and 15 (see Fig. 9) which are connected together by a short-circuiting connection 38 as indicated in Figure 5.

In order to effect the tilting movement, all the casings 1 are mechanically connected

together by means of a rigid bridge 42 of insulating material. An arm 43 engages with the bridge 42, the said arm being secured to the axle 44 of the controlling member 45.

Moreover a sleeve 45 is rotatably mounted on the axle 44 and is attached to the said axle through a helical spring 54. The sleeve 45 carries a disc 46 of insulating material which is provided on both sides with spring contacts 35. The spring contact 35 on the one side is conductively connected with an opposite spring contact 35 provided on the other side. In the arrangement for three-phase current, three pairs of such contacts are provided these contacts being preferably displaced relatively to one another through an angle of 120°. The fixed contacts 49 co-operating with the spring contacts 45 are mounted on suitable shields provided on both sides of the disc 46, these fixed contacts being connected on the one side with the terminal 36 and on the other side with the terminal 37.

An adjustable spring 46 tends to bring the apparatus into the connecting position or to fix it in the disconnecting position in the same way as a bell crank lever. An insulating rod 52 which is mounted in the two shields provided on both sides of the disc 46, passes through the slot provided in the disc 46 and serves for the purpose of limiting the movement of the disc. The rod 52 is secured in position by means of screw nuts 53.

The stator winding illustrated in Figure 5 is connected to the terminals 36 whilst the supply circuit is connected to the terminals 37.

The operation of the device just referred to is as follows:—

By moving the controlling member 45 from the disconnected into the connected position, the disc 46 is first of all taken along and thereby the stator is connected to the terminals 37, 36 and the contact knives 35 to the supply circuit. As the rotation continues, the casings 1 are tilted by the arm 43 by means of the bridge 42 until the resistances are completely disconnected. The reverse process takes place during the disconnecting operation. The object of the spring 54 is that according to the adjustment of its normal tension the switch 35 shall be disconnected before the resistances in the casing 1 are completely inserted into the circuit, similar to a quick-brake switch or the spring is tensioned sufficiently to disconnect the switch only when the resistances in the casings 1 are again completely inserted into the circuit.

As regards the construction illustrated in Figure 10 the overflow pipe 56 is to be specially mentioned, as it prevents any undesired overflow of the conducting liquid in

the passages 12 also in the case of a quick operation.

- 55 is a protecting casing for the whole of the apparatus, which casing is secured in such a way that it can be removed only when the apparatus is disconnected and the switch contacts are open, so that the construction of the casing 1 of conducting material cannot in any way become dangerous.
- 10 It is also to be pointed out that the solid resistance may be made of any suitable material which would not be affected by the conducting liquid. Carbon has been found to be especially favourable. Instead of using 15 mercury for the conducting liquid, any other liquid may be used which would not adhere to the substance used as the resistance, for instance water with a conducting addition, for instance salt or the like.
- 20 When the casing is not made of conducting material an electrode will necessarily have to be used which will have to be of such material that it will not be affected by the conducting substance.
- 25 What I claim is:—
1. In an apparatus of the character described adapted to control a plurality of circuits, a tilttable rheostat including solid resistances, each resistance being adapted 30 to be coordinated to each circuit, a chamber, a passage for liquid associated with each resistance, each passage being connected with said chamber, and a conducting liquid, said liquid being received within the cham-

ber in one position of the rheostat and adapted, when the rheostat is tilted, to flow into the passage and partly or wholly short-circuit the resistances, according to the position of the rheostat.

2. A rheostat as claimed in claim 1 characterized in that the chamber is common to all passages for all resistances.

3. A rheostat as claimed in claim 1 characterized by the provision of means insulating the resistances from each other.

4. A tilttable rheostat including solid electrically connected resistances, a conducting casing for the resistances, a chamber in said casing, a passage in said casing for liquid associated with each resistance, each passage 50 being connected with said chamber and a conducting liquid, said liquid being received within the chamber in one position of the rheostat and adapted when the rheostat is tilted to flow into the passage and partly 55 or wholly short-circuit the resistance, according to the position of the rheostat.

5. A rheostat as claimed in claim 1 characterized in that the resistances are shaped as portions of cones.

6. A rheostat as claimed in claim 1 characterized in that the resistances are shaped as portions of cones and are insulated from one another.

In testimony whereof I have signed my name to this specification.

RICHARD KELLENDORFER.
